US00D736994S

(12) **United States Design Patent**
Mittersinker et al.

(10) **Patent No.:** **US D736,994 S**
(45) **Date of Patent:** **** Aug. 18, 2015**

(54) **SMOKING ACCESSORY**

(75) Inventors: **Gregor Mittersinker**, Warwick, RI (US); **Aaron Abroff**, Acton, MA (US); **Laurent Manca**, Grandvaux (CH)

(73) Assignee: **Philip Morris Products S.A.**, Neuchatel (CH)

(**) Term: **14 Years**

(21) Appl. No.: **29/422,430**

(22) Filed: **May 21, 2012**

(30) **Foreign Application Priority Data**

Nov. 21, 2011 (EM) 001303150-0001
Nov. 21, 2011 (EM) 001303150-0002

(57) **CLAIM**

The ornamental design for a smoking accessory, as shown and described.

DESCRIPTION

FIG. 1 is a perspective view of the back, top, and left side of the design for a smoking accessory.

FIG. 2 is a right side view thereof,

FIG. 3 is a top plan view thereof,

FIG. 4 is a left side view thereof,

FIG. 5 is a bottom plan view thereof,

FIG. 6 is a front plan view thereof; and,

FIG. 7 is a back plan view thereof.

The broken lines in the drawings depict parts of the smoking accessory that form no part of the claimed design.

1 Claim, 7 Drawing Sheets
